UNITED STATES PATENT OFFICE

WILLIAM GOLDSTEIN, OF NEW YORK, N. Y.

DESIGN FOR A SHOE

Application filed July 2, 1931. Serial No. 40,401. Term of patent 3½ years.

To all whom it may concern:

Be it known that I, WILLIAM GOLDSTEIN, a citizen of the United States, and a resident of the city of New York, in the county of Bronx and the State of New York, have invented a new, original, and ornamental Design for Shoes, reference being had to the accompanying drawings, forming part thereof.

Fig. 1 is a side elevation of a shoe showing my new design.

Fig. 2 is a plan view thereof.

I claim:

The ornamental design for a shoe, as shown.

WILLIAM GOLDSTEIN.
